CLAIM

The ornamental design for a connector for the game controller, as shown.

DESCRIPTION

FIG. 1 is a top, front and side perspective view of a connector for game controller showing my new design;

FIG. 2 is a back view thereof.

FIG. 3 is a top view thereof.

FIG. 4 is a bottom view thereof.

FIG. 5 is a front view thereof.

FIG. 6 is a first side view thereof; and,

FIG. 7 is a second side view thereof.

The broken line portion of the figure drawings is included to show unclaimed subject matter only and forms no part of the claimed design.
